B. WEINBERGER,
DRIVING MECHANISM FOR SEWING MACHINES,
APPLICATION FILED OCT. 7, 1919.

1,413,083.

Patented Apr. 18, 1922.

UNITED STATES PATENT OFFICE.

BENJAMIN WEINBERGER, OF ST. LOUIS, MISSOURI, ASSIGNOR TO MARX & HAAS CLOTHING CO., OF ST. LOUIS, MISSOURI, A CORPORATION.

DRIVING MECHANISM FOR SEWING MACHINES.

1,413,083.

Specification of Letters Patent. Patented Apr. 18, 1922.

Application filed October 7, 1919. Serial No. 328,960.

To all whom it may concern:

Be it known that I, BENJAMIN WEINBERGER, a citizen of the United States, residing at the city of St. Louis and State of Missouri, have invented a new and useful Driving Mechanism for Sewing Machines, of which the following is a specification.

This invention relates to a driving mechanism for sewing machines.

10 The invention has special reference to power driven sewing machines, such as are in common use in factories for the manufacture of wearing apparel, and for other uses.

In the factories in which such sewing machines are used the machines proper are secured upon supports, in the form of tables or benches, and are usually driven by driving connections from a power driven shaft.

20 My present invention comprises mechanism for driving the sewing machine from a power driven shaft and includes a novel form of transmission device for driving the sewing machine; and an object of the invention is to provide a novel and efficient driving mechanism for sewing machines and the like, embodying the construction and arrangement mentioned, and operating in a more satisfactory manner than do the transmission mechanisms now in common use.

30 With the foregoing and other objects in view, I have produced and used a satisfactory embodiment of the invention and have illustrated the same in the accompanying drawings in which—

35 Fig. 1 is a side view, a part of one of the clutch members being in section, showing the transmission mechanism supported by the bench or table of a sewing machine.

40 Fig. 2 is an end elevation of the invention, parts thereof being in section.

Fig. 3 is a lower end elevation of the supporting bracket by which the mechanism is adjustably supported in connection with the bench or table, viewed from the line 3—3 of 45 Fig. 2.

As is well known, the sewing machines are screwed in operative positions upon the upper surface of a bench or table 1 and it has heretofore been common practice to drive the 50 machines from a power driven shaft 2 supported below the bench or table and driven by some form of motor or power mechanism. My invention comprises an improved supporting device for the shaft from which the 55 sewing machines are driven, and a novel

form of mechanism for driving the machines from the shaft.

Each journal bearing for the power driven shaft, and each independently operable transmission mechanism, are supported from 60 a hanger bracket secured in connection with the lower side of the bench or table. As shown, each hanger bracket comprises a threaded sleeve portion 3 flaring outwardly toward its upper end to form a flat portion 65 4 arranged to bear against the lower surface of the bench or table. The flat portion 4 is formed with a number of transverse slots 5 for receiving the bolts 6, by which the hanger bracket is held in connection with the 70 bench or table. The slots 5 permit any necessary adjustment of the hanger bracket, as may be required to avoid any fixed part of the bench or table or to effect proper adjustment or alinement of any journal bearing. 75 Each of the sleeves 3 is interiorly threaded.

An independent journal bearing for the shaft 2 is provided in association or connection with the transmission driving mechanism of each sewing machine. In the embodiment shown, each journal bearing is in the form of a sleeve composed of an upper portion 7 and a lower portion 8 secured together by screws 9 passing through ears in connection with one of said members and effecting threaded engagement within threaded holes in the other member. The lower member 8 of the journal bearing is provided 85 with an oil or grease cup or chamber, 10 to maintain the shaft in the condition of proper lubrication. 90

The journal bearing thus constructed is supported between the legs of a bifurcated 95 bracket 11, and threaded rods 12 are screwed through the alined holes in the legs of the bracket 11. There are only 2 of the rods 12, and one of said rods is supported by each leg of the bracket 11 so that said rods are 100 in axial alinement. The inner ends of the rods 12 are formed with reduced portions 13, seating within recesses on opposite sides of the journal bearing above described so that the journal bearing is pivotally supported by the inner ends of the alined rods 12. This construction permits sidewise adjustment of the journal bearing to bring the same into accurate alinement with any other journal bearing in which the shaft 2 is 105 110

journaled. This construction also permits vertical adjustment of the ends of the journal bearing to aline all of the journal bearings irrespective of any inclination in which the supporting hanger 3—4 may be mounted as a result of any unevenness of the lower surface of the bench or table. The outer end of each of the rods 12 is provided with an engageable portion 14 by which the said rod may be turned for purposes of adjustment. Nuts 15 are screwed onto the rods 12 and into locking engagement with the bracket 11 to hold the rods from turning as a result of the vibration of the machines when in operation. Provision is made for holding the journal bearing positively in proper position for supporting the shaft. As shown a pair of screws 16 are threaded through ears on the bracket 11 and have their lower ends engaging the upper member 7 of the journal bearing at opposite sides of the rods 12. The screws 16 will prevent oscillation of the journal bearing relative to the shaft 2 after proper adjustment has been effected. Nuts 17 on the screws 16 and engaging the ears of the bracket through which the screws are threaded lock the screws against becoming loosened as a result of the vibration of the parts when in operation.

The bracket 11 is formed with an internally threaded portion 18. Said bracket 11 is supported from the hanger bracket 3—4 by an adjustable connection 19 having right hand threads on one end thereof and left hand threads on the opposite end thereof to correspond with the threads formed in the bracket 3—4 and with the threads formed in the portion 18 of the bracket 11. Thus the connection 19 may be simultaneously threaded into the bracket 3—4 and the portion 18 of the bracket 11 in order to raise the bracket 11 to any desired adjusted position. Similarly, the bracket 11 may be lowered from one adjustment to another by proper turning of the connection 19. Nuts 20 on the threaded portions of the connection 19 may be forced into locking engagement with the bracket 3—4 and with the bracket 11, respectively, in order to prevent dislocation of any of the parts as a result of vibration caused by operation of the machines.

From the foregoing it is apparent that there is a co-operative relationship between the parts described, permitting the journal bearing to be raised or lowered or adjusted laterally, or inclined as required to obtain the necessary exactness of adjustment and to prevent improper alinement of the journal bearing relative to the shaft. My invention, so far as above described, completely and satisfactorily obtains that object and purpose of adjustably supporting the journal bearing in position to accommodate the shaft 65 without the slightest torsional strains.

My invention comprises, further, mechanism for driving the connection for operating the sewing machine from the shaft 2. As shown, such mechanism is in the form of a transmission clutch of novel construction 70 and mode of operation. The transmission clutch shown comprises a clutch member 21 attached to the shaft 2 and in constant rotation with the shaft when the shaft is driven. At its periphery the clutching member 21 75 is provided with a beveled flange or clutch portion 22. The co-operating clutch member comprises a pulley or wheel 23 provided with a flange 24 movable into and out of clutching engagement with the portion 22 of 80 the clutch member 21. The flange 24 preferably supports a band 25 of indurated fibre or other material appropriate for use to form the contacting surfaces of clutching members and the like. The pulley or wheel 85 23 has a hub 26 journaled upon an extended portion of the journal bearing 7—8, above described; so that the clutching member 21 is in constant rotation with the shaft 2 while the co-operating clutch member is journaled upon a stationary support and is therefore wholly free from any tendency to rotate with the shaft 2, except when the clutch members are engaged. This is an important 90 feature of my present invention because it 95 permits the sewing machines or other driven mechanism to be stopped very quickly, inasmuch as the transmission member 23 of the clutch is instantly freed from any tendency toward rotation other than its own momentum, the moment that it is disengaged from the clutch member 21; and the momentum of the clutch member 23 is immediately overcome by a brake device which functions for that result and also for the purpose of co-operating with the clutch member 23 to disengage the same from the clutch member 21. The sewing machine or other driven mechanism may be operated from the pulley or wheel 23 by a belt 27 or other appropriate 100 device. Obviously, a wheel or pulley of any desired size may be employed as required to operate the driven mechanism at the speed desired. The clutch members are preferably enclosed within a housing in 105 order to prevent the clothing of the operator from becoming caught or entangled in the operating devices and also to protect the operating devices from the accumulation of dust and lint, etc. As shown, the housing 110 comprises two members 28. The housing members 28 are hinged to the bracket 11 as shown at 29, so that the housing may be opened and closed conveniently. The housing may be held closed by a releasable retaining device 30. The housing is provided with appropriate openings for the belt 27 and for the brake device which co-operates 115 with the pulley or wheel member of the clutch.

A lever 31 is pivotally supported at the lower end of an arm 32 extending downwardly from the member 8 of the journal bearing. At a distance, toward one side of the pivot, said lever supports a brake device 33 arranged to bear against the beveled outer surface of the flange 24 which is on the periphery of the wheel or pulley 23. A spring 34 of the expansion type is interposed between the opposite end of the lever and the journal member 8 and the energy of said spring is employed to actuate the brake device 33 into engagement with the flange 24 of the wheel or pulley 23.

15 The lever 31 is provided with a bifurcated arm 35 which embraces the journal bearing 7-8. The arm 35 terminates adjacent to the end of the hub 26 of the wheel or pulley 23 at each side of the journal bearing, so 20 that by drawing downwardly the free end of the lever 31, the brake device 33 is disengaged from the wheel or pulley 23 and said wheel or pulley is forced into clutching engagement with the clutch member 21-22.

25 Immediately upon release of the lever 31, the spring 34 acts to cause the brake device 33 to disengage the wheel or pulley 23 from the clutch device 21-22, as stated. The lever 31 may be operated to close the clutch 30 by any desired device, as by a treadle connection 36.

The construction of the frictional clutch surfaces of the clutch members provides for the return of the clutch member 23 to "off" 35 position when pressure against said clutch member by the arm 35 of the setting lever is released. The inclined clutching surface on the periphery of the clutch member 22 tends to repel the clutch member 23 to "off" position, and this tendency is assisted by the 40 brake 33 cooperating with the inclined peripheral surface of the flange 24. As a consequence of this when pressure of the clutch lever arm 35 against the clutch member 23 is stopped, the inclined peripheral frictional clutch surface of the member 23 cooperates with the brake 33 acting on the 45 inclined surface of the flange 24 to disengage the clutch member 23 from the clutch member 22, permitting the brake 33 to stop 50 the clutch member 24.

From the foregoing it will be seen that my invention in every way obtains its ob-

ject. The different parts thereof may be varied as to specific construction and arrangement without departure from the principle and nature of the invention.

What I claim is:—

1. A device of the character described, comprising a pivoted journal bearing, a shaft journaled in said bearing, a clutch member attached to said shaft, a second clutch member on said bearing out of engagement with said shaft, a lever supported by said bearing for moving said second clutch member on said bearing into engagement with the clutch member which is attached to the shaft, and means for preventing the bearing from exerting lateral pressure and strain against the shaft when the lever is operated.

2. A device of the character described, comprising a pivoted journal bearing, a shaft journaled in said bearing, a clutch member attached to said shaft, a second clutch member on said bearing out of engagement with said shaft, a lever supported by said bearing for moving said second clutch member on said bearing into engagement with the clutch member which is attached to the shaft, means for preventing the bearing from exerting lateral pressure and strain against the shaft when the lever is operated, and a device supported by said lever for holding said second clutch member 80 out of engagement with the clutch member which is attached to the shaft.

3. A device of the character described, comprising a pivoted journal bearing, a shaft journaled in said bearing, a clutch member attached to said shaft, a second clutch member on said bearing out of engagement with said shaft, a lever supported by said bearing for moving said second clutch member on said bearing into engagement with the clutch member which is attached to the shaft, means for preventing the bearing from exerting lateral pressure and strain against the shaft when the lever is operated, and an actuator for holding said lever in position to hold the second clutch member out of engagement with the other one and yielding to permit said lever to move the second clutch member into engagement with the first-named clutch member.

BENJAMIN WEINBERGER.
